UNITED STATES PATENT OFFICE.

JOHN COOMBS, OF SPRINGFIELD, MISSOURI, ASSIGNOR TO THE SOUTHWESTERN IMPLEMENT COMPANY, OF SAME PLACE.

HAY-STACKER.

SPECIFICATION forming part of Letters Patent No. 291,694, dated January 8, 1884.

Application filed April 6, 1883. (No model.)

To all whom it may concern:

Be it known that I, JOHN COOMBS, a citizen of the United States, residing at Springfield, in the county of Greene and State of Missouri, have invented a new and useful Hay-Stacker, of which the following is a specification, reference being had to the accompanying drawings.

This invention relates to devices for stacking hay and straw; and it consists in certain improvements in the construction of the same, which will be hereinafter fully described, and particularly pointed out in the claims.

In the drawings hereto annexed, Figure 1 is a perspective view of my improved hay-stacker. Fig. 2 is a side view of the same. Fig. 3 is a rear view. Fig. 4 is a longitudinal vertical sectional view. Fig. 5 is a detail view in perspective of the carrier and its attachments. Fig. 6 is a plan view of the stacker complete. Fig. 7 is a detail view of the mechanism for operating the compressor-frame of the carrier; and Fig. 8 is a side elevation, showing the lifting and dumping positions of the stacker in dotted lines and full lines, respectively.

The same letters refer to the same parts in all the figures.

A A in the drawings designate the longitudinal base-beams of the stacker, which are supported upon the bolsters B B of an ordinary wagon running-gear. The beams A A support a pair of transverse braces, C and D, near the center and rear end, respectively, and from the center of the forward brace additional braces E E extend diagonally in a forward direction.

F F are uprights mounted vertically upon the ends of the cross-bars C and D, and having their ends connected with said cross-bars by inclined braces G G.

H H are the inclined track-rails, which are mounted upon the upper ends of the uprights F F, and have their lower ends secured to the forward ends of the braces E E, as shown.

Extensions I I are hinged to the lower ends of the track-rails H H by means of links J J, which permit the said extensions to be folded up upon the track-rails while the device is being moved from place to place. While the

device is in use the parts I I are folded down so as to rest upon the ground, as shown in the drawings.

K is the carrier, which is constructed of a set or series of teeth, L, connected by cross bars or braces N N at and near their rear ends. Said frame is provided with rearwardly-projecting brackets O O, forming bearings for shafts P, on which are journaled the grooved track-wheels Q and grooved pulleys R.

S is a long arm or lever extending rearwardly from the carrier-frame, and provided at its rear end with a roller, T, the object of which will be presently explained.

U is a toothed frame, termed the "compressor-frame," which is hinged to the rear end of the carrier, and provided with a pivoted rearwardly-extending arm or lever, V, having at its rear end a laterally-projecting stop, W.

X is a guide-rail mounted longitudinally upon the cross-bars C D, which are connected by said rail. Another similar rail, Y, is mounted above the first one upon brackets Z, which extend upwardly from the cross-bars C D.

Extending downwardly from the rear ends of the guides X Y is a curved or segmentally-slotted guide, A², and secured upon the side of the lower guide-rail, X, is a longitudinal trough-shaped guide, B², having at its rear end a slot, C², below which a stop or bracket, D², is secured.

At the front end of the trough B² is a hook, E².

F² is an arm projecting laterally from the rear end of the upper guide-rail, Y, and having a forwardly-projecting bracket or catch, G².

The hoisting-ropes H² are secured to the upper corners of the inclined track-rails, from whence they pass down over the grooved pulleys R of the carrier, thence over pulleys I² at the upper ends of the track-rails, and thence down over pulleys J², journaled at the lower corners of a frame, K², extending downwardly from the rear cross-bar, D, of the frame, with which it is connected by suitable brackets or hangers L². In this manner a low draft is secured, the advantages of which will be read-

ily appreciated. To the ends of the hoisting-ropes, which are suitably connected, the draft is directly attached.

The operation of this invention will be readily understood from the foregoing description, taken in connection with the drawings hereto annexed. The machine is conveyed to the stacking-place, where it is to be secured by means of stakes, or in any convenient manner. 10 The carrier is then to be lowered, and the load deposited upon it, which is usually done by means of suitable rakes or gatherers. Draft is then applied to the hoisting-ropes, and the carrier, with its load, is thereby raised upon 15 the inclined tracks. During its upward passage the carrier is gradually tilted by the arm or lever S, the roller T of which travels upon the under side of the guide-rail Y until it reaches the segmentally-slotted guide A², 20 whereby the carrier is tilted rearwardly. At the same time the lever V of the compressor-frame strikes the stop or bracket D², thereby forcing the compressor-frame in a forward direction and compressing and holding the load 25 securely upon the carrier. The latter continues its upward course until the top of the track is reached, and by this upward passage the pressure upon the lever of the compressor-frame is gradually lessened until it entirely 30 ceases, and the laterally-extending stop W of the lever V engages the catch G², whereby the compressor-frame is thrown back and the load dumped from said frame. The carrier is then permitted to drop or return by its own weight 35 to its original position. Before the carrier-frame reaches the ground the stop W of lever V engages the hook E², whereby the compressor-frame is thrown back and held in position, so as not to interfere with the load 40 which may be placed upon the carrier.

The trough B² serves as a guide for the lever V.

I claim as my invention and desire to secure by Letters Patent of the United States—

45 1. The combination of suitable inclined track-rails, the carrier moving upon the same, an arm or lever extending rearwardly from said carrier, guides for said arm or lever, a compressor-frame hinged to the carrier, an arm pivoted to said frame, and suitable guides for said arm, as set forth.

50 2. In a hay-stacker, the combination of the guide-rail X, the trough-shaped guide secured to the side of the same, and the pivoted compressor-arm moving in said guide, as set forth.

3. The combination of the carrier, the hinged compressor-frame, the arm pivoted to the same, a stud or stop projecting laterally from the rear end of said arm, a trough-shaped guide, and a hook at the front end of the same, as set 60 forth.

4. The combination of the carrier, the hinged compressor-frame, an arm pivoted to the same, a stud or stop projecting laterally from the rear end of said arm, a trough-shaped guide, 65 a slot at the rear end of said guide, and a stop or bracket secured under the said slot, as set forth.

5. The combination of the carrier, the hinged compressor-frame, an arm pivoted to the same, 70 a stud or stop projecting laterally from the rear end of said arm, the guide-rail Y, supported by suitable brackets, and the catch F² G², secured to said guide-rail, as set forth.

6. The combination of the carrier, the hinged compressor-frame, an arm pivoted to the same, a stud or stop projecting laterally from the rear end of said arm, a trough-shaped guide, a hook at the front end of the same, a slot at the rear end of the said trough, a stop or bracket 75 secured under the said slot, the guide-rail Y, supported by suitable brackets, and the catch F² G², secured to said guide-rail, as set forth.

7. The combination of suitable inclined track-rails, the carrier, an arm or lever extending 85 rearwardly from the same, a wheel or pulley at the rear end of said arm, the track or guide-rails X Y, the curved or segmentally-slotted guide A², the compressor-frame hinged to the carrier, the arm pivoted to the same, a stud 90 or stop projecting laterally from the rear end of said arm, a trough-shaped guide, a hook at the front end of said guide, a slot at the rear end of said trough, a stop or bracket secured under said slot, and the catch F² G², secured to 95 the guide-rail Y, as set forth.

8. The combination of the base-frame, the inclined tracks, the carrier, the hoisting-ropes, a frame extending downwardly from the rear end of the base-frame, and pulleys journaled 100 at the lower corners of the said frame, and serving to guide the hoisting-ropes, the draft upon which is thereby lowered, as set forth.

In testimony that I claim the foregoing as my own I have hereto affixed my signature in 105 presence of two witnesses.

JNO. COOMBS.
